Primary Examiner — Susan Bennett Hattan*Assistant Examiner* — Marie D. Fast Horse(74) *Attorney, Agent, or Firm* — Scott L. Harper; Griffith Bates Champion & Harper LLP(57) **CLAIM**

The ornamental design for a electronics enclosure, as shown and described.

DESCRIPTION

FIG. 1 is a perspective view of the electronics enclosure of the present invention;

FIG. 2 is a front view of the electronics enclosure of the present invention;

FIG. 3 is a back view of the electronics enclosure of the present invention;

FIG. 4 is a right side view of the electronics enclosure of the present invention;

FIG. 5 is a left side view of the electronics enclosure of the present invention;

FIG. 6 is a top view of the electronics enclosure of the present invention; and,

FIG. 7 is a bottom view of the electronics enclosure of the present invention.

The broken lines depicting a data port in FIGS. 1 and 2, and attachment holes in FIGS. 1 and 6, represent structural portions of the electronics enclosure that form no part of the claimed design.

1 Claim, 5 Drawing Sheets(56)
